UNITED STATES PATENT OFFICE.

PAUL FUHRER, OF DENVER, COLORADO.

COMBINED MOP AND WRINGER.

1,112,532.

Specification of Letters Patent.

Patented Oct. 6, 1914.

Application filed March 11, 1913. Serial No. 753,562.

To all whom it may concern:

Be it known that I, PAUL FUHRER, citizen of the United States, residing at Denver, in the county of Denver and State of Colorado, have invented certain new and useful Improvements in Combined Mops and Wringers, of which the following is a specification.

This invention relates to combined mops and wringers, and has as its object to provide a device of this class which is simple in construction and which has no parts liable to get out of order.

It is one aim of the invention to provide a wringing device for mops which is devoid of gears and may be readily manipulated to wring the mop.

The invention also aims to so construct the wringing device that it will not in any way interfere with the ordinary use of the mop.

Briefly stated, the device of the present invention includes a mop cloth clamping head to which one end of the mop cloth is connected and a rotatable head to which the other end of the cloth is connected, the last mentioned head being rotated through the medium of a crank-handle, and the invention has as one of its objects to provide a simple means for holding the crank-handle against rotation when the mop is being put to ordinary use so that the handle will not be liable to strike against objects or mar the same.

Further the invention contemplates the provision of means for securely holding the mop cloth against disengagement from the mop-cloth clamping head, and also to provide means for holding the support for the crank handle against turning movement about the handle of the mop.

For a full understanding of the invention reference is to be had to the following description and accompanying drawing, in which:

Figure 1 is a view in front elevation of the mop embodying the present invention. Fig. 2 is a side elevation thereof. Fig. 3 is bottom end view of the mop. Fig. 4 is a detail transverse sectional view on the line 4—4 of Fig. 2.

Corresponding and like parts are referred to in the following description and indicated in all the views of the accompanying drawing by the same reference characters.

In the drawing the handle of the mop

is indicated by the numeral 1 and at its lower end is provided with the usual ferrule 2. The handle 1 at its said lower end carries a mop cloth clamping head constructed to engage and hold one end of the mop cloth, showing of which has been omitted for the sake of clearness. The clamping head includes a fixed and a movable clamping section and the fixed section includes two members 60 each formed from a single length of wire bent upon itself as at 3 at a point between its ends, whereby to form spaced portions converging in the direction of the said ends as shown in Fig. 3 of the drawing, which portions adjacent the bend 3 are correspondingly bent as at 4, the said bends 4 being spaced apart, as clearly shown in Figs. 2 and 3. At a point suitably spaced from their ends the spaced portions of the members of the fixed section are bent as at 5 so as to form tangs 6 which are driven into the end of the handle 1, in the manner clearly shown in Fig. 1 of the drawing. As will be apparent from inspection of said figure and of Fig. 3, the members of the said fixed clamping section extend in opposite directions from the lower end of the mop.

For a purpose to be presently explained, spurs having shanks 7 and pointed at 8, are driven into the lower end of the handle 1 at points between the bends 5 of the corresponding spaced portions of the said members, the pointed ends 8 projecting a short distance below the said bends. The movable clamping section includes a head in the nature of a wire frame having a cloth-engaging bar 9 and spaced portions 10 which are slidably fitted between the bends 4 and are received in the bends 3 of the members 95 of the fixed clamping section, in such manner that the cloth-engaging bar 9 may be adjusted toward or away from the said fixed members. Above the bends 3, the spaced portions 10 are bent to extend inwardly as at 11 and thence upwardly beside the handle 1 as at 12, the upper ends of the said portions being bent toward the handle 1, as indicated at 13, whereby to form pintles pivotally fitted in eyes 14 100 formed by bending the spaced portions 15 of a clamping lever through the movement of which the movable section is adjusted. The clamping lever is formed from a single length of wire, which in addition to being bent to form the eyes 14, has an intermediate bend 105 16 so formed as to partly receive the handle

1 when the lever is in clamping position. Below the eyes 14 the spaced portions 15 are bent as at 17 to form eyes which pivotally engage the projecting ends of a pivot-
5 pin 18 which is fitted through the handle 1 and which is headed as indicated at 19.

It will now be apparent by reference to the foregoing and to the drawing that when the lever 16 is swung downwardly and outwardly from the handle 1, the movable clamping section will have its clamping bar 9 moved downwardly and away from the members which constitute the fixed clamping section and with the parts so adjusted 10 the end of the mop cloth may be inserted between the said bar 9 and the said members of the fixed clamping section. The lever 16 may then be swung upwardly to normal position, thereby bringing the clamping bar 9 15 into firm engagement with the end of the mop cloth and binding the material of the cloth in the kerfs between the spaced portions of the fixed members. By reference to Fig. 3 it will be noted that the spurs 8 are 20 located at opposite sides of the clamping bar 9, and it will be apparent that the pointed ends of these spurs will dig into the material of the mop cloth and prevent the same being pulled from engagement between the fixed 25 and movable clamping sections. It is to be observed that the bar 9 is slightly curved so that adjacent its ends it will project into the kerfs between the spaced portions of the fixed members of the head, so that the end 30 35 of the mop cloth will be drawn into the kerfs and securely held against slipping, and it will further be apparent that by reason of the engagement of the spaced portions 10 between the spaced bends 4 of the fixed 40 members, the movable section of the cloth clamping head is guided in its movement and cannot swing forwardly or rearwardly.

The wringing device includes, as before stated, a rotatable head with which the other 45 end of the mop cloth is connected and this head is carried by a support which is slidably adjustable along the mop handle so as to position the head near the mop cloth clamping head above described or to position 50 the same at a higher point upon the handle. The means provided for guiding the supporting member in its sliding movement upon the handle consists of a rod 20 secured at its ends as at 21 to the rear side 55 of the handle and it will be observed that this rod is co-extensive with the handle and except at its ends is spaced therefrom. The ends of the rod are secured in place by nails or screws, and the securing element for the 60 lower end of the rod engages through an opening in a cross-piece 22 which has its end portions projecting in opposite directions and at right angles to the line of extent of the rod 20, these projecting portions being 65 spaced from the handle 1. The support for

the wringer head is formed preferably from a single length of wire which between its ends is bent to form an eye 23 and beyond its ends as at 24 to form spaced portions 25. The eye 23 slidably fits the rod 20, as clearly 70 shown in Figs. 1 and 2 and the spaced portions 25, extending downwardly in rear of the handle 1 and near their lower ends are bent as at 26 to extend forwardly and downwardly as at 27. The spaced portions are 75 also bent as at 28 to form portions 29 which extend downwardly in front of the handle 1. For a purpose to be presently pointed out the spaced portions of the supporting member are bent to extend toward each other 80 forwardly of the handle 1 so that at their bends 28 they will be nearly in contact. As before pointed out, the cloth holding head of the wringer is to be rotated through the medium of a crank handle and the bearing 85 for this crank handle is formed preferably from a sheet metal blank which is folded to form several plies 30, the plies at their folds 31 receiving the lower ends of the portions 29 of the supporting member. The plies 20 90 are formed with registering openings 32 which constitute the bearing for the crank handle and it will be observed that the openings in the plies are so formed that the bearing opening will be flared as at 33 toward 95 each side of the bearing.

It is preferable that the head of the wringer and the crank handle for rotating the same be formed integral and from a single length of wire, this length being bent 100 at one end to form a mop cloth end receiving loop 34 which constitutes the head of the wringer and the wire adjacent this loop being bent as at 35 to form a relatively short bearing 36 which is received in the bearing opening 33. The bearing 36 is, however, of a length greater than the dimensions of the bearing and of less diameter than the bearing opening so that the said bearing portion may have rocking as well as rotative movement in its bearing. The wire beyond the bend 35 constitutes the crank handle which is indicated by the numeral 7 and is provided with a grip 38 whereby it may be rotated.

In order to prevent the crank handle being slipped through the bearing a washer 39 is fitted upon the bearing portion 36 and has wings 40 which are bent to receive the inner end of the crank 37. The portion of the 110 washer which projects beyond the bearing serves as a stop for the purpose stated.

In practice, the mop cloth is engaged at one end in the clamping head at the lower end of the mop handle and the clamping lever is swung at 16 into clamped position, the lower end of the cloth having been connected in any suitable manner in the loop 34 constituting the head of the wringer device. The supporting member is then swung 125 130

downwardly upon its guiding rod 20 until the head 34 is located immediately above and forwardly of the first mentioned clamping head. The crank handle 37 is then swung 5 toward the handle 1 until it engages behind the bends 28, whereupon it will be held against rotation and consequently against movement to position to interfere with the proper use of the mop. It will be apparent 10 that as the supporting member is slid down upon the handle 1 its spaced portions adjacent the eye 24 will ride beneath the projecting ends of the cross-piece 22 and the supporting member will be held against turning 15 movement about the mop handle. Should it be desired to wring the mop, the supporting member is slid upwardly until the mop cloth is stretched taut and the crank handle is then swung away from the handle 20 so as to disengage it from between the bends 28 of the supporting member and is rotated so as to twist the mop cloth and express the surplus water therefrom.

What is claimed as new is:

- 25 1. In a mop, a handle, a mop cloth clamping head carried by the handle, a supporting member slidably mounted upon the handle, a crank mounted for rotation and rocking movement upon the supporting member, 30 means for holding the crank against rotation, and means carried by the crank for the attachment of a mop cloth.
2. In a mop, a handle, a mop cloth clamping head carried by the handle, a support 35 slidably mounted upon the handle, a bearing carried by the support and having a bearing opening flared in the direction of its ends, a pivot member mounted in the said opening for rotation and for rocking movement, 40 means upon the support for holding the pivot member against rotation, and means carried by the said pivot member for the attachment of a mop cloth.
3. In a mop, a handle, a mop cloth clamping head, carried by the handle, a supporting member slidably mounted upon the handle and including spaced portions, a bearing carried by the said spaced portions, a crank having a pivot mounted for rotation and for 50 rocking movement in the bearing, the crank when rocked being adapted to engage between the spaced portions of the supporting member and thereby be held against rotative movement, and means carried by the pivot 55 for the attachment of a mop cloth.

4. In a mop, a handle, a mop cloth clamping head carried by the handle, a rod carried by the handle and co-extensive therewith, a supporting member formed from a single length of wire bent to form an eye slidably 60 fitting the said rod and to form spaced portions having bends substantially in contact, a bearing supported by the spaced portions adjacent to the said bends, a crank having a pivot mounted for rotation and rocking 65 movement in the bearing, the crank when rocked being engageable between the said bends in the spaced portions, whereby to be held against rotative movement, and means carried by the pivot for the attachment of a 70 mop cloth.

5. In a mop, a handle, a mop cloth clamping head carried by the handle, a rod carried by the handle and co-extensive therewith, a supporting member having an eye slidably 75 fitting the rod and having spaced portions extending beside the handle, a member carried by the handle and having portions projecting in opposite directions therebeyond and arranged to engage against the spaced 80 portion of the said member when the member is in one position of its sliding movement, thereby to hold the supporting member against turning upon the rod and upon the handle, a bearing carried by the sup- 85 porting member, a crank handle having a pivot rotatably mounted in the said bearing, and mop cloth attaching means carried by the pivot.

6. In a mop, a handle, a mop cloth clamping head carried by the handle, a bearing supported upon the handle and having a bearing opening, a crank formed from a single length of wire bent to form a loop to receive the mop cloth and form a pivot located between the crank proper and the said loop, the pivot portion being of a length greater than the length of the bearing opening and of a diameter less than the diameter of the said opening, whereby the said pivot 95 portion may have rotative and rocking movement in the opening, and a washer fitted upon the pivot portion and having wings bent to embrace the crank portion.

In testimony whereof I affix my signature 105 in presence of two witnesses.
